Filed Feb. 17, 1966, Ser. No. 1,084

Term of patent 14 years

(Cl. D58—12.6)

Fig. 9

FIG. 1 is an elevational view of one side of a stacking and nest bakery tray, showing my new design.

FIG. 2 is an elevational view of an adjacent side of a stacking and nesting bakery tray showing my new design.

FIG. 3 is a fragmentary top plan view of the side shown in FIG. 1.

FIG. 4 is a fragmentary bottom plan view of the side shown in FIG. 1.

FIG. 5 is a fragmentary bottom plan view of the side shown in FIG. 2.

FIG. 6 is a fragmentary cross sectional view taken on the line 6—6 of FIG. 1.

FIG. 7 is a fragmentary cross sectional view taken on the line 7—7 of FIG. 2.

FIG. 8 is a fragmentary cross sectional view taken on the line 8—8 of FIG. 2.

FIG. 9 is a perspective view thereof on a reduced scale, the circular pattern on the base being continuous throughout as shown in FIGS. 3, 4 and 5.

The sides of the tray opposite FIGS. 1 and 2, respectively, are the same as FIGS. 1 and 2.

I claim:

The ornamental design for a stacking and nesting bakery tray, as shown and described.
